ELECTRIC SWITCH

Andrew Brown and Denis Alexander Tomlin, London, England, assignors to International Standard Electric Corporation, New York, N. Y., a corporation of Delaware

Application January 8, 1949, Serial No. 69,882

Claims priority, application Great Britain
January 22, 1948

1 Claim. (Cl. 246—134)

The invention is concerned with electrical switches.

The main feature of the invention is an electric switch comprising a number of contact sets and means for selecting and operating any one or any combination of the contact sets, wherein selection of a contact set or sets to be operated is carried out without disturbance of any contact set.

One possible application of this type of switch is for use in railway signal and/or points control systems of the kind using multi-position motor-driven rotary control switches for controlling the selection and setting up of any one of a number of different routes outgoing from a particular position as described in the U. S. Patent 2,241,906 which was issued on May 13, 1941. Such systems require less apparatus than alternative relay systems and each switch can accommodate many contacts and can be used for a number of routes equal to the number of positions to which it can be set. This has been done by having a rotor, carrying a number of cams, being arranged to stop in a number of different angular positions. These different positions are allocated to different routes, and the cams are cut to give the desired contact arrangement in each position. The routes which conflict with one another are allocated to positions on the same switch and interlocking between them is automatic, since the rotor can be in only one position at a time. However, conflict between routes on different switches cannot usually be avoided. Previous switches of the kind described have had certain disadvantages. In passing from the "home" or "normal" position of the rotor to say position 5, positions 1-4 must be passed through. These positions may have been allocated to routes which conflict with routes already set up on other switches. Provision has therefore had to be made so that when the first switch passes through these conflicting route positions it does not break down the routes set up on the other switches. At the same time it has had to be arranged that if, by some fault, the first switch should stop in any of these conflicting route positions, no dangerous condition will arise. Further disadvantages have been, (1) that a switch could stop by fault between two route positions, (2) the rotor assembly has had to be specially made for every particular switch, and (3) that a change in a circuit or interlocking required the removal of the switch rotor and alteration in the cutting of the cams.

A switch, according to the present invention, while achieving the economy of space and contacts of the motor-driven multi-position switches, has none of the above disadvantages when used in railway signalling systems.

The invention will be particularly described in relation to two embodiments thereof shown in the accompanying drawings, in which:

Fig. 1 shows an elevation, part sectioned, of a switch according to the first embodiment;

Fig. 2 shows a diagrammatic elevation of the switch shown in Fig. 1 from a viewpoint at right angles to that used for Fig. 1;

Fig. 3 shows schematically circuits for the driving and positioning cams of the switch shown in the previous two figures;

Fig. 4 is a diagrammatic elevation of a switch according to the second embodiment of the invention;

Fig. 5 illustrates diagrammatically the method adopted

2

in this second embodiment for ensuring the engagement of one of the code bars with the contact sets, whilst

Fig. 6 shows in some detail, part of the operating method outlined in Fig. 5, this view being of a limited nature, only three selecting bars and one code bar being included;

Fig. 7 is a section on the line X—X of Fig. 6;

Fig. 8 shows in schematic form the circuit arrangements for the switch forming the subject of Figs. 4-7.

Fig. 9 shows a diagrammatic elevation of a modified switch of the same general kind as shown in Fig. 4, whilst

Figs. 10A to 10D show different positions which may be taken up by a latch forming an important part of this modified switch.

15 The general operating arrangements of the switches according to three embodiments of the invention will now be described. In the first, the motor-driven rotor of prior art switches as shown for instance in U. S. Patent No. 2,260,292 is retained, but instead of cams, it has 20 a rotor, around which are attached a number of code bars extending parallel to the axis of the rotor and spaced around the periphery thereof, each having a distinctive cut in the free end thereof. The code bars are so placed that in each of the route positions one of the bars can 25 engage with a predetermined number of contact sets in accordance with the distinctive cut in the ends of the code bars. A prime mover and cams are associated with the rotor to drive it into and prove its position. This having been proved, a solenoid, motor-driven cam or other electrically operated mechanism causes relative movement between the rotor and the contact sets. According to 30 how the code bar is cut, a predetermined selection of these contact sets is operated. Therefore, any desired contact set or combination of contact sets may be operated 35 in each of the route positions.

The code bars are made easily detachable so that each can be removed and its cutting altered without interfering with the use of the switch in the remainder of its route positions. Since the solenoid or other mechanism 40 is not operated until the rotor is in the exact position desired, passing through other route positions has no effect on the contacts, and can be ignored from an interlocking point of view.

In the second form of the switch, no rotor is used and 45 the code bars are in parallel slides. They are individually selected by electro-magnets, and lifted to operate the contacts by solenoids, motor-driven cams, or other means. This second arrangement has the advantage of being quicker operating than the first switch utilizing the 50 rotor.

In Figs. 1 and 2 a switch of the rotor type is shown with its rotor 1 mounted on a shaft 1A together with 7 double-sided cams 2 . . . 8 along with one part 9A of a magnetic clutch indicated generally at 9. The shaft 1A is rotatably mounted in two bearings 10, said bearings being carried on pivoted arms 11 joined together to form the armature cooperating with a magnet 12. In Fig. 2 the rotor is shown as having six code bars 13, one of them being immediately beneath the insulating studs 14 of the contact sets 15. When the magnet 12 is energized, the rotor is raised and the uppermost code bar 13 is brought into engagement with the insulated studs of certain of the contact sets. Where the code bar has been cut away the insulated stud 14 is not contacted and contacts 15 remain unoperated, but where the code bar has been left the contacts are operated. This is clearly shown in Fig. 1.

If it is desired to operate the route allocated to position A of the rotor, the circuit is made over the contacts 70 of the route switch and other appropriate switches (not shown) to prove that no conflicting route has been set up and from there to the wipers of cams 3 and 6 simultaneously. The cams 2 . . . 8 consist of suitably cut discs 2e, 2f . . . 8e, 8f of copper or bronze riveted to insulated discs 2b . . . 8b, respectively as shown in Fig. 1. The cam surfaces 6e and 6f therefore form one unit 6 in electrical contact with each other. A contact is made between the three cam units 6 and 6a, 7 and 7a, 8 and 8a, by means of metallic rings 16 between them. Separate wipers 2c, 75 2d, 3c, 3d, 4c, 4d, 5c, 6c, 6d, 7c, 7d, are provided for corresponding cams. An additional wiper 17 is provided

to complete the circuit to relay ZR. If the cam 6 is in the position shown in Fig. 3, which position corresponds to route A, it will be seen that a circuit is made for relay ZR via battery, winding of relay ZR, wiper 17, metallic ring 16, contact surface of cam 16, wiper 6c, lead A, route allocation selector switch (not shown), positive battery. Relay ZR having operated, the clutch coil 9 is energized over positive battery $zr1$ front coil 9, to negative battery (Fig. 3). When the clutch is energised it attracts to it a clutch armature plate 18, which is held by a spring spider 19 connected to part 9a on the rotor shaft. The main shaft 20 is driven by an electric motor (not shown), and drives the magnet coil portion 9b of the clutch through gears 21. The main drive motor may be either continuously running or started by the operation of a contact (not shown) controlled by the ZR relay. When the clutch armature plate 18 is attracted by the energised rotating magnet coil, friction between surfaces is sufficient to drive the rotor. This continues until position A is reached, when the circuit for relay ZR is broken by the insulating segment on cam 6 as shown in Fig. 3. The cam 2 is used to continue the drive after relay ZR is released, until the rotor is accurately positioned. When the clutch coil 9b is deenergised the armature 18 is released, and the drive to the rotor is broken, so that the rotor stops in position A. With the rotor in this position a circuit is made for relay ZCR over cam 3, as shown in Fig. 3, and the relay is operated via negative battery, winding of relays zcr , wiper 17a, negative battery, contact surface of cam 3, wiper 3c, lead A, route selecting switch (not shown), positive battery. Cams 3/5 are assembled similarly to the cams 6/8. When relay ZCR is operated a circuit is provided for the contact operating magnet 12 via: positive battery, contact $zcr1$; winding of magnet 12, negative battery, causing the magnet 12 to attract its armature, and in so doing to lift the whole rotor 1. When the rotor is lifted the code bar 13 is engaged with the insulated studs 14 of the contact sets, thus operating a particular combination of the sets. All the contact sets shown are make contacts, but break or changeover contacts can be used when required.

A switch constructed according to the second embodiment of the invention, the parallel slide-bar type is the subject of Figs. 4-8, Fig. 4 showing an assembly of selecting and code bars. Resting along the top of the code bars 13 are the contact levers 22, which operate the contact sets 15. The lifting arms 23 are raised by cams or eccentrics (as at 24) and are pivotted so that their motion is parallel to that of the contact levers 22. The code bars 13 and the selecting bars 25 are assembled together with separating guides 26 in a box (see Fig. 7), so that the selecting bars 25 can be moved longitudinally in a direction normal to the plane of the paper and vertically and the code bars 13 vertically only. The lifting of a selecting bar raises its associated code bar. The sets of code and selecting bars are separated by the thin sheet-metal guides 26 which are anchored so that they only have a small amount of side-play.

When a selecting bar has been operated, that is, moved longitudinally, its engaging detents 27 become positioned above the lifting arms 23 (Fig. 5), so that the raising of the lifting arms raises the selecting bar and its associated code bar. The selecting bars which are not operated have their clearing detents 28 above the lifting arm, so that the raising of the arm does not affect them.

Since the lifting arms 23 and the contact levers 22 are parallel, the latter are lifted by the same amount, no matter which pair of selecting and code bars acts as the link between them.

Fig. 6 shows in greater detail the method of operating the selecting bars. The selecting bars each have cut away from them a number of similar notches 29. The notches except for one different one of each bar, are equally spaced. This different notch in each case is displaced to the right, and no bar has the notch in the same position displaced. A switch to handle 12 routes will therefore require 12, 12-notch selecting bars, and 12 code bars. Cams 30 are engaged with the notches so that when a cam is turned through 90° all the notches in that position are brought into line as shown at the central notch in the figure. This brings all except one of the selecting bars into the unoperated position. The selecting bar that has a displaced notch in that position is however moved to the left as is indicated by dotted lines, so that its engaging detents 27 are above the lifting arms 23.

Each selecting cam is operated by its own electromagnet 31, 32, 33 . . . through cooperating armatures 31a . . . 33a to which are coupled linkage levers 31b . . . 33b, respectively.

5 The stop arm 34 prevents any selecting bar from being lifted unless it is in the operated position; a bar in the operated position allows the stop arm to drop into a cooperating slot 35 adjacent one end of selecting bar 25, which slot is provided for the purpose.

10 Electrical contact cams are provided on the same shaft as the lifting cams or eccentrics but are not shown in the drawing. These cams are similar to those described for the first embodiment. Some are used to drive and position the lifting cams, while others are used to isolate the selecting magnets when the lifting cams are operated. In Fig. 8 only there are indicated the contacts which are required to close when the selecting cams are operated.

15 If it is desired to operate route A (see Fig. 8) a circuit is provided from the route key via the contacts of other interlocking switches to cam C of the interlocking switch, and by a contact made in the normal position to the selecting magnet SMA. This operates the associated selecting bar via the selecting cam, and locks the remainder of the bars in the unoperated position, in the manner as 20 has already been described and shown in Figs. 6 and 7. The contact of the selecting cam $sma1$ front extends the circuit already provided for cam D, to cam G, which, in the normal position, connects to the clutch coil Z, which is energised over an obvious circuit.

25 This clutch, which may be similar to that described for the first embodiment, drives the lifting and selecting cams. Immediately the cams leave the normal or unoperated position, the circuit for the selecting magnet is broken at cam D, and to the clutch coil Z by the contact $sma1$ and cam G. The clutch remains energised however, over cam H which is cut to be disconnected in both the normal and reverse positions, and connected in intermediate positions. Therefore the drive is continued until the reverse position is reached, when the circuit for the clutch is broken, and the cams stop, the selecting bar cam having been turned through 90°. The lifting arms having been raised, the contact sets required for route A are operated. One of these contacts, $ac1$ (which is only operated in that route position) extends the original 30 circuit from cam D (now in the reverse position), to relay ZCR, which operates and proves that the switch is in the desired route position.

35 When it is desired to break down the route, the original circuit is broken, and relay ZCR is released. This will effect the route signals being changed to red, but will not release the route contact selection. When it is considered safe to break down this selection the release circuit for route A is made, which over $ac2$ front energises the ZNR relay. Over $znr2$ front the clutch coil is energised over the reverse contact of cam G. The cams are thereafter driven until they are in the normal position, when the circuit for relay ZNR is broken, and the clutch is de-energised.

40 Where a route requires a larger number of contact sets than are normally available on one switch, there may be attached to it one or more extension units. These units will have code bars, contact levers, and contact sets similar to the main switch, but the code bars will be lifted by means of push rods 35 interposed over the code bars of the main switch as shown in Fig. 6. The extension units will therefore be mounted in layers above the main switch.

45 In order to guard against the possible false contact due to failure or breakage of studs on the contact springs, contact sets required to be normally closed are mounted below the contact lever, or equivalent contact spring, and held there by the initial tension on the contact lever. In this case, the breakage of any operating stud has the effect of opening rather than closing the contact.

50 In the first embodiment, as well as in the second, a motor-driven cam can be used to lift the code bar assembly (e. g. the rotor). This motor may be an individual drive motor or, common motor driving a cam through clutches as pointed out previously in connection with the description of Fig. 1. Other variations possible include the use of self-latching armatures with special-release arrangements.

55 In a third embodiment, it is proposed to incorporate in a standard arrangement two sets of contacts, one operated as before when the lifting arms 23 are raised whilst the

other set requires for its operation that the arms 23 shall be lowered. This scheme is shown generally in Fig. 9 and it will be seen that an electromagnet 37 is included in place of the eccentric lifting device 24 indicated in Fig. 4. There are shown the usual code bars 13, selecting bars 25 and contact levers 22, but the latter is arranged not only to actuate an upper contact set 15, but also a lower set 38. The lifting arms 23 co-operate, at the end away from the electromagnet 37, with a latch 39 which has a stepped slot. An end elevation of this latch is shown in Fig. 10A, wherein the slot 40 can be clearly seen, whilst Figs. 10B, 10C and 10D will help in an understanding of the operation of this device.

As before the arms 23 on being lifted operate the make-contact sets 15 so arranging the setting up of the required route. The normal relative positions of the arm 23 and the latch 39 are shown in Fig. 10A, it being understood that the latch is pivotted about the spindle 41. The arm 23 on being raised knocks against the surface 42 of the slot 40 so that as seen in Fig. 10B, the latch is displaced clockwise about its pivot 41. When the control switch of the route is released, the signals are arranged to go to danger immediately the upper contact set 15 is broken, but the arrangement is designed to ensure that no further route involving the contacts which have just been operated can be set up on any switch until a well-known back-lock has freed them for further service.

This desired result is achieved as follows: The magnet 37 releases the arms 23 but the fall is checked by the step 43 in the latch slot 40. This condition is shown in Fig. 10C. When the setting up of further routes is permissible the back-lock controls the quick operation of electromagnet 44. This attracts an armature extension 45 of the latch and as will be seen from Fig. 10D, the latch 39 is rotated counter-clockwise and the arm 23 is released from the step 43 and drops down in normal position so that the contacts 38 are remade. The magnet 44 soon afterwards releases and the latch 39 returns to its normal vertical position shown in Fig. 10A. The

circuit arrangements are such that elements of the route which has been broken down may now be used in the setting up of the routes.

While the principles of the invention have been described above in connection with specific embodiments, and particular modifications thereof, it is to be clearly understood that this description is made only by way of example and not as a limitation on the scope of the invention.

What is claimed is:

An electric switch comprising a plurality of code bars operable to engage through contact levers with a first plurality of contact sets, any bars being operable to effect the operation of one or more of the said contact sets, a plurality of selecting bars one for each of the said code bars, means which engage notches in the said selecting bars operable to effect movement in a first plane of any one selecting bar at a time and a pivotted lever operable to be displaced after said movement has taken place so as to engage with the said particular selecting bar, displacing the latter and its associated code bar in a second plane thus operating the appropriate contact set or sets via their contact levers.
